CLAIM

The ornamental design for an arthroscopic jig, as shown and described.

DESCRIPTION

FIG. 1 is an arthroscopic jig of the new design;
FIG. 2 is a perspective view of the arthroscopic jig;
FIG. 3 is a front elevational view of the arthroscopic jig;
FIG. 4 is a rear elevational view of the arthroscopic jig;
FIG. 5 is a left-side elevational view of the arthroscopic jig;
FIG. 6 is a right-side elevational view of the arthroscopic jig;
FIG. 7 is a top plan view of the arthroscopic jig; and,
FIG. 8 is a bottom plan view of the arthroscopic jig.

The broken lines shown in FIG. 1 illustrate environment that forms no part of the claimed design.

1 Claim, 6 Drawing Sheets
